UNITED STATES PATENT OFFICE.

GEORGE HENRY MAAS, OF MILWAUKEE, WISCONSIN.

BOX-FASTENER.

No. 909,918.

Specification of Letters Patent.

Patented Jan. 19, 1909.

Application filed June 29, 1908. Serial No. 441,005.

To all whom it may concern:

Be it known that I, **GEORGE HENRY MAAS**, a citizen of the United States, residing at Milwaukee, county of Milwaukee, and State of Wisconsin, have invented new and useful Improvements in Box-Fasteners, of which the following is a specification.

My invention relates to improvements in that class of lock and seal for which Letters 10 Patent of the United States, No. 878,215, was issued to me February 4, 1908, the same being adapted to be used in connection with shipping crates or cases.

The construction of my invention is explained by reference to the accompanying 15 drawings in which,

Figure 1 represents a plan view of the cover retaining mechanism, removed from the cover, showing the parts which form 20 the hasp supporting loop as they are cut preparatory to being bent into the required shape. Fig. 2 represents a vertical section of one corner of a shipping case and cover with the cover retaining mechanism drawn 25 on line $\alpha-\alpha$ of Fig. 1. Fig. 3 represents a perspective view of a keeper formed for the reception of the hasp. Fig. 4 represents a detail view showing the inside view of the wall of the case, a vertical section of the 30 cover and the keeper and a side view of part of the fastening mechanism coöoperating with such parts. Fig. 5 is a vertical section of the sealing member, which is inserted above the locking mechanism in the cover.

Like parts are identified by the same reference figures throughout the several views.

1 represents the cover retaining keeper which is rigidly affixed to the vertical wall 2 of the case, by a plurality of nails or 40 screws 3. A wire hasp is pivotally connected with the cover through the loop 6 and seal supporting plate 7. The plate 7 is rigidly connected with the underside of the cover 8 by a plurality of nails or screws 9 and 45 said cover and plate are locked in engagement with the wall 2 by turning the horizontal member 10 of the hasp beneath the vertical wall 11 of the keeper, as shown in Fig. 2. The hasp is formed of a piece of 50 wire and comprises the horizontal member 10, the vertical member 12, horizontal member 13, vertical inverted U-shaped member 14 and horizontal member 15, which terminates in a U-shaped bend 16. The end of the 55 U-shaped bend 16 is adapted to bear against

the inside of the supporting loop 6 and serves as a spring to force the hasp into locking engagement with the keeper 1. It will be understood that the horizontal members 13 and 15 and vertical member 14 taken 60 together, serve as a lever for throwing the horizontal member 10 out of engagement with the keeper, when desirous to unlock the cover from the case.

For convenience of construction, the hasp 65 retaining loop 6 and the plate 7 are formed integrally from a piece of sheet metal, which is first cut, as shown in Fig. 1, when the respective arms 18, 18, are curved downwardly and inwardly from the position, shown in 70 Fig. 1, to that shown in Fig. 4, when the lower ends of said arms are brought together around the lower end of the vertical member 12, as indicated in Fig. 4, the respective arms 18, 18, being provided with semi-circular recesses 19, 19, which, as they are brought together, form an aperture for the reception of the vertical member 12 of the hasp. The upper end of the vertical member 75 12 is supported from said plate 7 through 80 the lug 20, which lug 20 is formed integrally with the plate 7, said plate 7 being first provided with a U-shaped cut 21, as indicated in Fig. 1, when that part of the plate within the cut 21 is bent downwardly 85 from the position shown in Fig. 1 to that shown in Fig. 4, when it thus serves as a support for said cover retaining hasp.

22 is an aperture formed in the cover for the reception of the U-shaped member 14 90 of the operating lever and seal. The plate 7 is provided with a circular aperture 23 terminating upon one side with two U-shaped recesses 24 and 25, for the reception of the vertical bend 14 of the operating lever, as is 95 more clearly shown in Figs. 1 and 2.

It will be understood that when desirous to throw the horizontal locking member into engagement with the inclined wall 11 of the keeper, the vertical member 14 of the operating lever is thrown into the recesses 24 and 25, whereby the cover 8 is locked in engagement with the case. When however, it is desirous to remove the cover, the vertical member 14 of the lever is thrown back to the 100 center of the aperture 22, whereby the horizontal member 10 is dis-engaged from the keeper, when the cover may be readily removed or raised from the case.

To prevent the locking mechanism from 110

being tampered with or disengaged from the case without disclosing such fact, I have provided my device with a sealing mechanism 26. The sealing member 26 comprises the horizontal disk 27, annular sleeve 28, which sleeve is formed at right angles to and is connected with said horizontal member 27 by a plurality of vertical fingers 29. Said seal also comprises a plurality of outwardly diverging tangs 30, all of which parts are formed integral with said disk 27. When the locking mechanism has been brought into engagement with the keeper, said sealing plate is inserted through the aperture 22 of the cover and aperture 23 of the plate 7, whereby the vertical loop 14 of the operating lever is retained in the recesses 24 and 25 of said plate, and said cover retaining mechanism is prevented from being thrown out of locking engagement with the keeper. It will be understood that as the sealing device is thus forced into position, the retaining members 30 spring outwardly of their own resiliency beneath the fastening plate 7, as shown in Fig. 5, whereby said sealing device is retained in place and it becomes impossible to dis-engage the locking mechanism without first breaking the plate 27 from the annular collar 28 of the sealing member. To facilitate in breaking the seal, the plate 27 is provided with apertures 31, 31, for the reception of a breaking tool, which tool is inserted through one of the apertures 31, when by prying upwardly, the delicate connections 29 between the annular collar 28 and the plate 27 are readily broken, when the operating arm of the locking mechanism may be moved to the center of the aperture 22, whereby its arm 10 will be dis-engaged from the keeper, when the cover may be thrown open or removed from the case.

The front wall 11 of the keeper 1 is preferably formed at an angle to the vertical, converging inwardly and downwardly from its upper side toward the wall of the case, whereby as the arm 10 of the hasp enters said keeper, it will be automatically turned toward the wall of the case, preparatory to being thrown back into locking engagement beneath the lower edge of the hasp by the resilient action of the arm 16, as the cover is brought to its closed position.

Having thus described my invention what I claim as new and desire to secure by Letters Patent is,

1. In a device of the described class, the combination of a shipping case, a keeper rigidly affixed to the walls of the case, a cover provided with an aperture for the reception of the operating arm of the cover retaining hasp, a supporting plate secured to the inside of said cover, having a central aperture concentric with and of slightly less diameter than the aperture of said cover, a hasp supporting loop formed integrally with

said supporting plate and a hasp, comprising a fastening member adapted to engage the lower edge of said keeper, a vertical member pivotally supported from said loop, a horizontal member extending laterally from said loop to and beneath the aperture of said cover and an operating member extending vertically into the apertures of said cover and supporting plate. 70

2. In a device of the described class, the combination of a shipping case, a keeper rigidly affixed to the walls of the case, a cover provided with an aperture for the reception of the operating arm of the cover retaining hasp, a supporting plate secured to the inside of said cover, having a central aperture concentric with and of slightly less diameter than the aperture of said cover, a hasp supporting loop formed integrally with said supporting plate and a hasp comprising a fastening member adapted to engage the lower edge of said keeper, a vertical member pivotally supported from said loop, a horizontal member extending laterally from said loop to and beneath the aperture of said cover, an operating member extending vertically into the apertures of said cover and supporting plate, a seal comprising a horizontal plate and an annular collar extending laterally beneath said plate and connected therewith by a plurality of breakable members, said annular collar being provided with a plurality of outwardly diverging resilient arms, adapted by their resilient action when said seal is in place, to engage the lower side of said supporting plate and prevent said seal from being withdrawn from the cover. 80 85 90 95 100

3. In a device of the described class, the combination of a shipping case, a keeper rigidly affixed to the walls of the case, a cover provided with an aperture for the reception of the operating arm of the cover retaining hasp, a supporting plate secured to the inside of said cover, having a central aperture concentric with and of slightly less diameter than the aperture of said cover, a hasp supporting loop formed integrally with said supporting plate and a hasp comprising a fastening member adapted to engage the lower edge of said keeper, a vertical member pivotally supported from said loop, a horizontal member extending laterally from said loop to and beneath the aperture of said cover, an operating member extending vertically into the apertures of said cover and supporting plate, a seal comprising a horizontal plate, provided with apertures for the reception of a removing instrument, and an annular collar, extending laterally beneath said plate and connected therewith by a plurality of breakable members, said annular collar being provided with a plurality of outwardly diverging resilient arms, adapted by their resilient action when said seal is in 110 115 120 125 130

place, to engage the lower side of said supporting plate and prevent said seal from being withdrawn from the cover.

4. In a device of the described class, the combination of a shipping case, a keeper rigidly affixed to the walls of the case, a cover provided with an aperture for the reception of the operating arm of the cover retaining hasp, a supporting plate secured to the inside of said cover, having a central aperture concentric with and of slightly less diameter than the aperture of said cover, and two radial recesses extending laterally past the circle described by said central aperture and formed for the reception of the operating member of the cover retaining hasp, a hasp supporting loop formed integrally with said supporting plate and a hasp comprising a fastening member adapted to engage the lower edge of said keeper, a vertical member pivotally supported from said loop, a horizontal member extending laterally from said loop to and beneath the aperture of said cover, an operating member extending vertically into the apertures of said cover and supporting plate, a seal comprising a horizontal plate, provided with apertures for the reception of a removing instrument, and an annular collar, extending laterally beneath said plate and connected therewith by a plurality of breakable members, said annular collar being provided with a plurality of outwardly

diverging resilient arms, adapted by their resilient action when said seal is in place, to engage the lower side of said supporting plate and prevent said seal from being withdrawn from the cover. 35

5. In a device of the described class, the combination of a shipping case, a cover for said case, a locking device for securing said cover to said case, said cover being provided with an aperture above said locking device, a seal supporting plate secured to the inner side of said cover, provided with an aperture concentric with the aperture of said cover and a seal for closing said aperture above said locking mechanism, said seal comprising a horizontal plate and an annular collar extending laterally beneath said 50 plate, a plurality of breakable members connected at one end with said horizontal plate and at their opposite ends with said collar and a plurality of outwardly diverging resilient members adapted when said seal is 55 in place, to spring outward beneath and engage the lower side of said supporting plate and prevent said seal from being withdrawn from the cover, all substantially as and for the purpose specified. 60

In testimony whereof I affix my signature in the presence of two witnesses.

GEORGE HENRY MAAS.
